UNITED STATES PATENT OFFICE.

JOHN D. OLDS, OF FORT WAYNE, INDIANA.

BALANCED SLIDE-VALVE.

SPECIFICATION forming part of Letters Patent No. 319,115, dated June 2, 1885.

Application filed June 23, 1884. (No model.)

To all whom it may concern:

Be it known that I, JOHN D. OLDS, of Fort Wayne, in the county of Allen and State of Indiana, have invented certain new and useful Improvements in Balanced Slide-Valves; and I do hereby declare that the following specification, taken in connection with the drawings furnished and forming a part of the same, is a clear, true, and complete description of my invention.

The object of my improvements is to so far reduce the friction of a slide-valve with its seat that it can be more readily controlled by a dynamometrical governor than any prior valve of this class of which I am cognizant.

My improved slide-valve belongs to that general class in which a balance-plate is employed at the inner end of a hollow piston, which occupies a cylinder in the steam-chest cover; and my invention consists of certain novel combinations of certain elements, all of which, in various forms, have heretofore been employed.

After fully describing the mechanism illustrated in the drawings, the features deemed novel will be specified in the several clauses of claims hereunto annexed.

Referring to the drawings, Figure 1 is a longitudinal section of a steam-chest containing my improvements. Fig. 2 is a side view of the steam-chest. Figs. 3 and 4 are side and bottom views of the balance-plate piston detached. Fig. 5 is a side view of the slide-valve detached. Fig. 6 is a side view of the steam-chest with its cover detached and the balance-plate piston removed from its cylinder for disclosing the comparative areas of said cylinder and the valve-seat.

The valve-seat A, with its steam-ports *a* and exhaust-ports *b*, is as heretofore. The slide-valve B is a plain box-valve, having, as heretofore, a flange, *c*, at its back and no flanges at its ends near its face. The valve B is moved to and fro by the valve-rod *d*, provided with the usual stuffing-box, and attached to the valve by way of a rectangular strap, *d'*, which surrounds the valve. The steam-chest cover C is provided with a cylinder, *e*, differing from prior cylinders for balanced valves in the matter of its proportions to the area of the steam and exhaust ports. Heretofore such cylinders have had a diameter never greater than

about equal to the distance between the outer sides or edges of the two induction-ports, and therefore a considerable proportion of such valves were unfavorably exposed to steam-pressure.

On referring to Fig. 6 it will be seen that the cylinder *e* has an internal diameter of such extensive proportions that it includes within its circular outline or sectional area the entire area of the two induction-ports *a* and the exhaust-ports *b*. To be within one portion of my invention it is essential that said cylinder be at least large enough to thus wholly include that portion of the valve-seat which is occupied by the several ports; but it can be made still larger without departure from my invention or materially affecting the results desired. The balance-plate piston D is hollow, and has at its inner end a flange, *f*, which projects beyond each end of the valve-seat A, said flange serving as a guide, with which the back flange, *c*, of the valve is in steam-tight contact. The outside diameter of said piston D is sufficiently less than the inside diameter of the cylinder *e* to enable the piston to be provided with a bull-ring, *g*, backed up by springs *h*, and the metallic packing-rings *i*. This combination of cylinder, piston, bull-ring, springs, and packing-rings, in itself considered, is substantially as heretofore employed within steam-engine cylinders; but I believe I am the first to thus organize them with a balance-plate for a slide-valve. I am aware, however, that such balance-plate pistons have been packed by means of soft packing and glands, and also by metallic packing-rings; but these latter were not backed up by springs. As a result of the use of said well-known combination of bull-ring, springs, and packing-rings in this novel combination with a balance-plate piston and slide-valve, I not only obtain a good steam-tight joint, but I am enabled to properly pack a larger piston than I find it practicable to pack either with solid packing or with such soft packing as can be used with glands, as heretofore employed. I also find that there is less liability of undue adhesion of the piston with its cylinder than with other varieties of packing, and therefore the adjustment of the balance-plate can be effected with greater facility, as will be hereinafter further considered in connection with adjusting devices. The

cylinder *e* has a cover, *k*, securely bolted in place and provided with a central aperture, *k'*. When the valve-chest is on the side of a cylinder, it is provided with an oil-cup on its upper side, which will deliver a lubricant upon the valve adjacent to its contact with the balance-plate piston; but when said chest is on top of a cylinder the oil-cup is located in said aperture *k'*, so that in either case all steam-pressure which may occur within the cylinder and piston can be relieved by way of said aperture. Other arrangements for oiling can be provided without in any manner affecting my invention. The cylinder-cover *k* is bored and tapped at four equidistant points over the corners of the steam-ports for the reception of four adjusting-screws, *l*, which at their inner ends abut against the surface of the outer end of the piston, or in suitable seats formed there-in. At two opposite points, substantially over the center of the exhaust-port *b*, the cylinder-cover is bored to receive the two lifting-screws *m*, which, at their inner ends, occupy tapped holes in the piston, and having shoulders which abut against the surface of the cover said screws can be relied upon for lifting or moving the piston away from the valve. Each of these screws *l* and *m* is preferably of the thumb or hand screw varieties, (although ordinary heads can be employed,) so that they may be conveniently manipulated from time to time. It will be seen that the adjusting-screws *l* enable the loose adjustment of the guiding-flange *f* into proper relations with the flange *c* on the back of the valve, while the lifting-screws *m* are free, and that the latter can then be relied upon for sustaining the weight of the piston, or, in other words, for wholly relieving the valve from pressure on its seat. The use of the two lifting-screws thus located enables both sides of the guiding-flange *f* to be separately controlled and maintained in exact parallelism with the back of the valve. It is not broadly new to thus provide for forcing a balance-plate piston toward a valve, nor for lifting it from the valve; but heretofore the periphery of the upper end of the piston has been threaded and provided with a lifting-nut bearing upon the steam-chest cover, and four adjusting-screws similar to mine passed through the cover and engaged with yielding surfaces on top of the guiding-flange of the balance-plate piston. As compared with said prior construction, I

am enabled to better pack my piston in its cylinder, and to independently adjust each end of the guiding-flange; and in this connection I can make it readily obvious wherein my ring-packing backed up by springs enables adjustments of the piston more readily than gland-packing. Gland-packing must be set up tightly to secure a tight joint, and therefore the piston is strictly limited to a longitudinal movement, whereas the ring-packing as employed by me enables the piston to be slightly canted or tipped in either direction without impairing the steam-tight joint between the rings and the walls of the cylinder, and, moreover, while the gland-packing is liable to be unduly adhesive, the spring-backed metallic packing always permits a free adjustment.

Having thus described my invention, I claim as new and desire to secure by Letters Patent—

1. The combination, with a steam-chest, a single slide-valve, its seat, and ports, of a balance-plate provided with a hollow cylindrical piston, and opposite the valve-seat, in the cover of the steam-chest, a piston-cylinder which includes within its sectional area that portion of the valve-seat which is occupied by the induction and exhaust ports, and also the main portion of said seat, substantially as described, and for the purpose specified.

2. The combination of the balance-plate piston provided with valve-guiding flange, the steam-chest, its cover, and cylinder, the four adjusting-screws, and the two lifting-screws, located at opposite sides of the piston, substantially as described.

3. The combination of the steam-chest cover and its cylinder, the balance-plate piston, the bull-ring, its springs, and the metallic packing-rings, substantially as described, whereby said piston, without impairing the packed joint between it and its cylinder, can be canted or tipped, as set forth.

4. The combination of the slide-valve, its seat, the steam-chest having the large cylinder in its cover opposite the valve-seat, as described, the balance-plate piston, its valve-guiding flange, its packing-rings, and the adjusting and lifting screws, substantially as described.

JOHN D. OLDS.
